US0D1037577S

(12) **United States Design Patent** (10) **Patent No.:** **US D1,037,577 S**
(45) **Date of Patent:** **** Jul. 30, 2024**

(54) **PET GROOMING TOOL**

(71) Applicant: **Zhejiang Kelaisiman Industry and Trade Co., Ltd.**, Zhejiang (CN)
(72) Inventor: **Yiping Lin**, Zhejiang province (CN)
(**) Term: **15 Years**
(21) Appl. No.: **29/937,609**
(22) Filed: **Apr. 16, 2024**
(51) LOC (14) Cl. **30-99**
(52) U.S. Cl. **USPC D30/158; D30/199**

Primary Examiner — Susan Moon Lee

(57) **CLAIM**

The ornamental design for a pet grooming tool, as shown and described.

DESCRIPTION

FIG. 1 is a front, left and top perspective view of a pet grooming tool showing my new design;

FIG. 2 is a rear, left and bottom perspective view thereof;

FIG. 3 is a left view thereof;

FIG. 4 is a right view thereof;

FIG. 5 is a front view thereof;

FIG. 6 is a rear view thereof;

FIG. 7 is a top view thereof; and,

FIG. 8 is a bottom view thereof.

The broken lines illustrate portions of the pet grooming tool that form no part of the claimed design.

1 Claim, 8 Drawing Sheets
